CLAIM

I claim the ornamental design for a snore inhibitor, as shown and described.

DESCRIPTION

FIG. 1 is a front plan view of the snore inhibitor of my new design, the back plan view being a mirror image thereof; FIG. 2 is a side view thereof, the opposite side being a mirror image thereof;

FIG. 3 is a top plan view thereof;

FIG. 4 is a bottom plan view thereof;

FIG. 5 is a front plan view of a modification of the snore inhibitor of my new design, the back plan view being a mirror image thereof;

FIG. 6 is a side view of FIG. 5, the opposite side being a mirror image thereof;

FIG. 7 is a top plan view of FIG. 5; and,

FIG. 8 is a bottom plan view of FIG. 5.

The surfaces of the snore inhibitor not shown are plain and unornamented.
